UNITED STATES PATENT OFFICE.

ASHBELL BARNUM, OF GREEN ISLAND, NEW YORK.

FOLDING CENTER-BOARD.

SPECIFICATION forming part of Letters Patent No. 377,134, dated January 31, 1888.

Application filed June 17, 1887. Serial No. 241,594. (No model.)

To all whom it may concern:

Be it known that I, ASHBELL BARNUM, a resident of Green Island, in the county of Albany and State of New York, have invented 5 certain new and useful Improvements in Folding Center-Boards; and I do hereby declare that the following is a full, clear, and exact description of the invention, that will enable others skilled in the art to which it appertains 10 to make and use the same, reference being had to the accompanying drawings, and to the letters of reference marked thereon, which form a part of this specification.

Similar letters refer to similar parts in the 15 several figures therein.

My invention relates to improvements in folding center-boards; and it consists of the novel construction and combination of parts hereinafter described, and pointed out in the 20 claims.

The objects of the invention are set forth in connection with the following description.

Figure 1 of the drawings is a side elevation of a boat provided with my improved center-board folded within a slot in the keel of the boat. Fig. 2 is a similar view showing the board unfolded and projecting from the keel. Fig. 3 is a view in perspective of one of the board-sections detached. Fig. 4 is a cross-section of same, taken at the broken line $x-x$ in Fig. 3, on enlarged scale. Fig. 5 is a horizontal section of a portion of the boat, taken at the broken line $x-x$ in Fig. 8, showing the board folded, as shown in Fig. 1. Fig. 6 is a similar view showing the board unfolded, as shown in Fig. 2. Fig. 7 is a plan view of a sheet-metal blank, which is bent into the form shown in Fig. 3 in forming the board-sections. Fig. 8 is a cross-section taken at the broken 40 line $x-x$ in Fig. 5, showing the sections exaggerated in thickness and shape, for convenience of illustration. Fig. 9 is a similar cross-section taken at broken line $x-x$ in Fig. 6.

My improved center-board B is shown in 45 position for use on the boat A in Fig. 2, and is adapted to be folded up when out of use and housed in a slot, K', in the keel K. It may be thus folded wholly within the keel, as shown in Fig. 1, where it will be wholly protected 50 from injury in shallow water, and by reason of its novel construction can be wholly housed

within the keel without any projections within the boat.

The center-board is made up of sections C, preferably of sheet metal, pivoted at their ends upon supporting and connecting slats or bars F and G, as will be more fully explained hereinafter. Blanks are first struck out or cut from sheet metal of about the form shown in Fig. 7. These blanks are then bent along the broken lines shown in Fig. 7 into the form shown in Figs. 3 and 4, in which the walls C' C' are about right-angular to the unbent portion and in cross-sectional outline parallel to each other, but convergent longitudinally from 65 one end of the section C to the other, presenting a trough-like appearance, having the opening gradually contracted from one end to the other of the section. The side walls are provided with pivot-apertures C² and C³, one in 70 each end. The contracted ends of the several sections are thus pivoted upon a slat or bar, G, inserted between the side walls of the contracted ends through the pivot-holes C' in such a manner that the side walls of each section 75 slightly overlap the bottom or unbent portion of each succeeding contiguous section. The other ends of the sections are pivoted in a similar position to two bars, F F, placed on the outer side of the walls C', each wall being independently pivoted upon its contiguous bar F by means of the rivets or pivots R, except that the first pivot, R', may extend through from one bar F to the other, forming a pivot or fulcrum for the operating-lever L, one end 80 of which is secured to the section so pivoted at R², the position of the lever being shown by dotted lines in Fig. 6. The other end of the lever is connected by link L' with the stem H', which passes up through an ordinary stuffing-box, J, into the boat, and may be provided with any convenient handle, as H. The bars F are provided with right-angular flanges F', by which they may be secured to the bottom of the slot in the keel, or to the floor-timbers E 85 and keelson D, when the slot passes entirely through the keel, as by the screws S.

It will be seen by an inspection of Fig. 9 that the sections are thus firmly secured upon each side, and that their stability or power of resisting a lateral or side strain is proportional to the relative lengths of the altitude and base 90 100

UNITED STATES PATENT OFFICE.

FREDRICK C. BAUER, OF PHILADELPHIA, PENNSYLVANIA.

SOAP COMPOUND.

SPECIFICATION forming part of Letters Patent No. 377,135, dated January 31, 1888.

Application filed March 5, 1887. Serial No. 229,844. (Specimens.)

To all whom it may concern:

Be it known that I, FREDRICK C. BAUER, of Philadelphia, in the county of Philadelphia and State of Pennsylvania, have invented a new and Improved Soap Compound, of which the following is a full, clear, and exact description.

My improved soap compound is designed for the use of mechanics, laborers, and others requiring a soap that will quickly and thoroughly remove grease and dirt from the hands and face.

My invention consists in combining with finely granulated porous material—such as sawdust—a quantity of soap of any approved manufacture.

In carrying out my invention I take granulated porous material, preferably sawdust, and screen it to secure uniformity of fineness, and I take hard soap of any desired quality and dissolve it in water, in about the proportion of a quarter of a pound of soap to a pint of water, and I boil the same until the solu-

tion is complete. I thoroughly mix the sawdust with the soap solution, and afterward spread it out to dry, and when dried it is ready for use.

My improved soap compound is used by moistening it with water and rubbing it thoroughly upon the skin.

I am aware that cakes or bars of soap have contained sawdust as one of their constituents, and I do not claim the same as of my invention; but I am not aware that a soap in granular form has been composed of sawdust or equivalent vehicle charged with soap.

Having thus fully described my invention, I claim as new and desire to secure by Letters Patent—

A granular soap compound consisting of a porous vehicle—such as sawdust—charged with soap, substantially as set forth.

FREDRICK C. BAUER.
